UNITED STATES PATENT OFFICE.

LEE P. HYNES, OF ALBANY, NEW YORK, ASSIGNOR TO CONSOLIDATED CAR-HEATING COMPANY, OF ALBANY, NEW YORK, A CORPORATION OF WEST VIRGINIA.

DOOR-CONTROL SYSTEM.

1,396,757.

Specification of Letters Patent.

Patented Nov. 15, 1921.

Application filed April 16, 1920. Serial No. 374,322.

To all whom it may concern:

Be it known that I, LEE P. HYNES, a citizen of the United States, residing at Albany, in the county of Albany and State of New York, have invented certain new and useful Improvements in Door-Control Systems, the following being a full, clear, and exact disclosure of the one form of my invention which I at present deem preferable.

For a detailed description of the present form of my invention, reference may be had to the following specification and to the accompanying drawings forming a part thereof.

My invention relates to the electrical control of doors, particularly a pair of car doors which normally operate in unison, their door-engine valves being worked by a single circuit. These doors move together to close and draw apart to open. Since each of them may individually strike an obstruction when closing, such as a belated passenger, they are each provided with a yielding shoe on its forward edge and either shoe is arranged to reverse the movement of both doors if a passenger should be hit. It may also happen that only one door of the pair will be in use at a time, the other being kept closed and a seat turned down in front of it, or one door of the pair may stick fast and refuse to open or close or be retarded more than the other. It is also important that when a shoe yields, it should not act to reverse other doors in the car than the pair to which the shoe pertains. It is also necessary in some cases that all the doors on one side of a train or a certain fraction of a train should be operated simultaneously in a group by one man from a given point of control. If such duty be assigned to a man on the train, it is necessary that in closing them, the particular door or doors where the man is stationed should be excepted from the common control of the group, so that he can lean out of the excepted door, or step therefrom onto the station platform and watch from outside the car the group of doors which he is closing and then after closing them he can reenter the train and close the excepted door apart from the others. These and other conditions of car-door operation are provided for in the arrangement described and claimed herein.

Referring to the drawing wherein the door-closing circuit wires are distinguished

by small crosses, A, A represent two duplicate doors each provided with a door engine C², the two engines being controlled by a common valve K of which the door-opening valve magnet is indicated at O¹ and the door-closing magnet at C¹. The two doors move toward each other to close and each is provided on its forward edge with an ordinary yielding shoe B which when pressed toward the door acts to close a switch D. Each door is provided with two contacts W and S which, as the door travels, slide along in contact with stationary bars or strips G, F, E, T, R and P. We may assume that the doors are closed, as represented in the drawing, and all of the circuits are open. The door-opening wire 1, which extends to other doors, will then be connected to battery H by a switch, such as the push-button O and wire 9, or a similar distant button O. Then all of the group of doors controlled by the wire 1 will be opened simultaneously. At each door, or pair of doors as shown herein, the current will flow from wire 1 by wire 10, back-stop contacts of button Q, wire 4, short strip P, contact S, short strip E at the left, wire 5, short strip E at the right, long strip F and wire 6, to door-opening valve-magnet O¹, going thence to ground. The valve-magnet O¹ will be of the well known type which requires only a momentary excitation to start the door engine. Then the engine will continue to operate the door until, at the end of the door run, it automatically throws its own valve to door-stopping position ready for the next trip in the opposite direction whenever the door-closing magnet C¹ is momentarily excited. As soon as the doors start from their closed position, the contact S at the left leaves the short strips E and P and engages the long strip F, while at the right the corresponding contact S will leave short strip E, but remain in contact with long strip F. The effect of this is to break, at two points in series, viz. at the two strips E, the door-opening circuit I have just traced which includes the wires 4, 5 and 6 and the valve-magnet O¹. The lack of symmetry in the arrangement of strips at the right and left sides of the doors is for the purpose of producing at the said contacts S and strips E the aforesaid two breaks in series, so, if one door and its contact S should stick and fail to start, or should be held closed for a long period, the break in

the door-opening circuit will still be insured at the other contact S by the starting of the other door. In like manner when the doors are open contacts W will bridge short strips 5 T and R in the door-closing circuit but will depart from their strips when the doors start to close. It will be evident therefore that the starting of the doors in either direction acts to break the circuit which has caused 10 the starting.

Assuming the doors to be open, it is manifest that contacts W have left the long strips G, G on each side, and now bridge the short strips T and R as aforesaid, while the 15 contacts S are both off from the long strips F. By this bridging of the strips T and R the door-closing circuit, including wires 7 and 8, with the closing valve-magnet C¹, is now complete, and if a current impulse 20 now arrive at wires 7 from the other supply wire 2 via wire 3, by the closing button which is here shown, or some distant button it will momentarily excite the magnet C¹ and start both doors on their closing run. 25 On starting it is obvious that contacts W leave the short strips T and R and engage the long strips G, while contacts S engage the respective long strips F. By thus leaving strips T and R the doors, at starting, 30 have broken at their strips, the door-closing circuit which has initiated the start, as heretofore described. It is also clear that each door not only breaks at starting the valve-magnet circuit which initiated the 35 start, but also, at the end of its run, closes contacts in the valve-magnet circuit which is to initiate the next start in the opposite direction. Thus in closing, the contact S, by bridging short strips P and E closes contacts which are in the door-opening circuit 40 and opening magnet O¹ which is to initiate the next start in the opening direction.

If the double doors shown herein are those at which is stationed the man who operates 45 the group of doors dominated by wires 1 and 2, or by train-wires connected thereto, it is desirable to except these doors from the group operation, and for this purpose I provide the button Q. This button normally 50 bridges at its back-stops a gap in the door-opening circuit through wires 4, 5, 6 and opening magnet O, this gap being located between wires 4 and 10 and when opened by the pressing of button Q cuts off the 55 door-opening circuit from supply wire 1. This occurs only at this one pair of doors, all others in the group remaining connected to the wire 1 and their opening circuits subject to current impulses therefrom. Thus 60 the pressing of button Q isolates these particular doors from others in the group, and at the same time connects battery H directly to the opening magnet O¹. When the train stops at a station, the doorman will press button Q, thereby opening all the doors in the 65

group including his own. When the train is ready for starting off, he can, by pressing button C, cause all the doors to close including his own; but by also pressing button Q he will neutralize at his own doors, the effect of 70 button C, or, if his own doors have closed or started to close, they will immediately open as soon as button C is released if button Q is still held down. This gives the doorman complete control of all doors in the 75 group and, in addition, an independent control of his own doors.

It should also be observed that in the event of the door-shoe meeting an obstruction, the consequent closing of a switch D 80 at any door would energize the opening magnets at all the doors in the group, if both contacts S were symmetrically connected to wire H in multiple instead of in series, provided any one door should stick or be 85 kept permanently closed. To avoid that, the contacts S are connected in series, as shown herein, by means of the short strips P and E, and wire 5. Hence every switch D, at the time it is connected to the long strips G and 90 F by means of contacts S and W is isolated from the main supply wire 1 and its closure by the door-shoe will energize no opening-magnet except its own. The circuits which are dominated by the respective door-shoe 95 switches D are door-opening circuits branching at the point 13 from the door-opening magnet O¹ and including the long strips F and G and the battery H. These may be termed energizing circuits and are both open 100 at strips F and G when the doors are closed to prevent unauthorized opening of the doors by manipulating the shoes. The strip F at the right is kept in engagement with contact S when the door is closed in order 105 to maintain the operating door-opening circuit from the common control wire 1 to the door-opening magnet O¹ via wires 4, 5 and 6, but the emergency circuit at the right is still open, when the door is closed, between the 110 contact W and the strip G. When either door moves away from its closed position the aforesaid operating circuit is opened, while each door, as it moves away from its closed position, closes the gap in its emergency circuit between G and F, leaving its emergency circuit subject to its door-shoe switch D, until the door is more or less fully opened.

What I claim as new and desire to secure 120 by Letters Patent is:

1. The combination with a pair of doors having a common control magnet, of a yielding shoe for each door, separate branch circuits from said magnet, and switches connected to the two door shoes and independently controlling said circuits.

2. The combination with a pair of doors having a common control magnet and separate door engines, of a yielding shoe for 130

- each door, separate branch circuits from said magnet, switches in the said circuits controlled respectively by the two door-shoes, a control wire extending to other doors, and means for isolating the door-shoe switches from the said control wire. 5
3. The combination with a pair of doors having a common control magnet and separate engines, of a yielding shoe for each door both shoes controlling the said magnet, a control wire extending to other doors, and two sets of contacts between said wire and said magnet, said sets being in series with each other and operated by the respective doors to isolate the door-shoe control from the said wire. 10
4. The combination with two doors having separate engines with a common control magnet therefor, of a yielding shoe for each door, switches operated by the respective door-shoes and acting on the said magnet, a common control wire extending to other doors, a contact on each door connected to the door-shoe switch and engaging stationary strips which are connected respectively with said magnet and with a source of current, and supplementary contacts for isolating the said switches from the common control wire. 15
5. The combination with a pair of doors having separate door-engines with a common door-opening magnet, of a common control wire extending to other doors, an operator's switch for energizing said control wire, a circuit from said control wire to the said door-opening magnet, and two sets of contacts in series in said circuit and controlled respectively by the two doors. 20
6. The combination with a pair of doors having separate door engines with a common door-opening magnet, of a common control wire extending to other doors, an operator's switch for energizing said control wire, an operating circuit between said control wire and said door-opening magnet containing contacts which are closed when the door is closed, two emergency door-opening circuits controlled respectively by the yielding door-shoes of the respective doors but containing contacts which are open when the doors are closed, and automatic means for opening the contacts in the said controlling circuit when either door is opened and closing the contacts in either emergency circuits when its corresponding door is opened. 25
7. The combination with a pair of doors, of separate engines therefor, a door-opening circuit controlling both engines, and contacts in said circuit opened by the movement of either door from its closed position. 30
8. The combination with a pair of doors, of separate engines therefor, a door-opening circuit controlling both engines, and two sets of contacts in series in said circuit controlled by the two doors respectively. 35
9. The combination with a pair of doors, of separate shoe-operated contacts for each of the respective doors, and door-opening means for both doors controlled by either one of said contacts, whereby the shoe on one door may cause both doors to open. 40
10. The combination with a pair of doors, of separate engines therefor, a door-closing circuit under manual control for closing both doors simultaneously, means for opening both doors simultaneously, and two switches for said means, one connecting with a line circuit, the other acting to break said line-circuit connection and energize the said means separately. 45
